UNITED STATES PATENT OFFICE.

ROBERT S. DRUMMOND, OF DETROIT, MICHIGAN, ASSIGNOR TO DETROIT STEEL PRODUCTS COMPANY, OF DETROIT, MICHIGAN, A CORPORATION OF MICHIGAN.

METALLIC WINDOW-SASH.

1,095,561.

Specification of Letters Patent.

Patented May 5, 1914.

Application filed April 24, 1913. Serial No. 763,352.

To all whom it may concern:

Be it known that I, ROBERT S. DRUMMOND, a citizen of the United States of America, residing at Detroit, in the county of Wayne and State of Michigan, have invented certain new and useful Improvements in Metallic Window-Sashes, of which the following is a specification, reference being had therein to the accompanying 10 drawings.

The invention relates to metallic window-sashes of that type in which the transversely-arranged division bars of the sash are united to each other by the one passing through an aperture in the other. Usually 15 sashes of this type are formed of T-bars having molded heads, and various expedients have been employed for joining these bars to each other.

20 With the present invention the sash comprises a combination of molded and plane or flat head T-bars, the former being apertured for the passage of the latter. This avoids cutting through the entire head of 25 the molded bar, as the thickness of the head of the flat T-bar is less than that of the molded section.

20 In the drawings: Figure 1 is a perspective view showing two transversely-arranged 30 sash bars joined to each other. Fig. 2 is a sectional elevation thereof. Fig. 3 is a perspective view of the molded bar. Fig. 4 is a similar view of the plane T-bar. Fig. 5 is a view similar to Fig. 3, showing a modified 35 construction. Fig. 6 is a perspective view similar to Fig. 1 of the construction shown in Fig. 5. Figs. 7, 8, 9 and 10 are cross sections of variously modified molded bars.

A is a sash bar having a molded T-head 40 B and a plane web or stem portion C. D is a transversely-arranged sash bar, which has a plane flat head E and web or stem F. To secure these two bars to each other the bar A is apertured at G to correspond to the 45 section of the bar E. The portion G' of this aperture, which corresponds to the web F of the bar D, is formed in the web C of the bar A, while the portion of the aperture G², which corresponds to the head E, is formed 50 in the head B of the bar A.

In assembling the sash, the bars D may be threaded through the apertures in the bars A and when properly positioned are secured

from displacement. The bars may be secured to each other in various ways, but, as 55 shown in Figs. 1 to 4, the web F of the bar D is notched at H in alinement with the web C of the bar A. The latter is then indented, as shown in Fig. 2, at I, which drives the metal into the notch H and interlocks 60 the bars.

In Fig. 5, a modified construction is shown, in which the web C of the bar A is transversely slotted at J, so as to permit of deflecting the section K at the end of the aperture G' sufficiently to admit the notched web F of the bar D. After the bars are properly positioned the deflected section K is driven back and will engage in the notch H to interlock the bar.

70 My improved construction has the advantage that the bars may be engaged with each other without cutting through the head of one of them or bending or deflecting them from normal shape. At the same time the 75 appearance produced by the sash when completed is as pleasing as that employing only bars with molded heads, and the construction is stronger than where the head of one bar is cut through.

80 As shown in Figs. 1 to 6, the molded heads of the bars are of the usual concave form. It may, however, be desirable at times to employ different shaped heads such as shown in Figs. 7 to 10.

85 What I claim as my invention is:

In a metallic window sash, transversely-arranged sash bars respectively formed with a plane flat and a molded T-head, the head and web of the molded bar being of a 90 greater depth respectively than the head and web of the flat head bar and the web and head of the molded bar being provided with apertures corresponding respectively to the cross-section of the web and head of 95 the flat head bar, there being a notch in the web of the flat head bar, and the web of the molded head bar being indented into said notch to form an interlock between said bars.

100 In testimony whereof I affix my signature in presence of two witnesses.

ROBERT S. DRUMMOND.

Witnesses:

JAMES P. BARRY,
HENRI E. BOWMAN.
